(57) CLAIM

The ornamental design for a pitcher, as shown and described.

DESCRIPTION

FIG. 1 is a top perspective view of a pitcher showing our new design;

FIG. 2 is a front view of the pitcher.

FIG. 3 is a back view of the pitcher.

FIG. 4 is a right side view of the pitcher.

FIG. 5 is a left side view of the pitcher.

FIG. 6 is a top view of the pitcher; and,

FIG. 7 is a bottom view of the pitcher.

All of the broken lines in the drawings are included for the purpose of illustration and form no part of the claimed design.
